(57) **CLAIM**

The ornamental design for a shoe bottom, as shown and described.

DESCRIPTION

The sole FIGURE is a plan view of a shoe bottom showing my new design.

The broken lines in the sole FIGURE illustrate unclaimed portions of the shoe bottom and form no part of the claimed design.

The relative depths and three dimensionality between the surfaces of the shoe bottom form no part of the claimed design.

1 Claim, 1 Drawing Sheet(56)
